Attorney.

UNITED STATES PATENT OFFICE.

WILLIAM S. BURKE, OF CHICAGO, ILLINOIS.

WINDOW-SASH.

1,248,451.

Specification of Letters Patent. Patented Dec. 4, 1917.

Application filed September 8, 1916. Serial No. 119,072.

To all whom it may concern:

Be it known that I, WILLIAM S. BURKE, a citizen of the United States, residing at Chicago, in the county of Cook and State of Illinois, have invented new and useful Improvements in Window-Sashes, of which the following is a specification.

This invention relates to windows and particularly to the sashes for windows which, through the use of this invention, 10 may be easily removed from the window frames.

The object of the present invention is to provide a window frame with a simple, inexpensive, and reliable means for releasing 15 both the upper and lower sashes from the grooves in the sides of the window frame, and from the sash cords without having to withdraw nails or screws when repairs, 20 cleaning or painting is required.

Another object of the invention is directed to the attachment of the sash cords to the sash, by means of hook-like terminals on the outer ends of the cords that engage 25 with the under side of the sashes and are held in engagement therewith when the sashes are in operative position, means being provided to catch the hooked ends of the terminals and hold the sash cords when the 30 sashes are removed.

Other details of construction will be set forth in the following specification and illustrated in the accompanying drawings, in which:

35 Figure 1 is a perspective view of a window complete provided with the improvement, a portion of the window frame being broken away;

Fig. 2 is a vertical longitudinal sectional 40 view of the window frame, the edges of the sashes being shown in elevation, and

Fig. 3 is a detail perspective view of one corner of a window sash showing the sash cord holding means.

45 In the drawing, 10 indicates the window frame as a whole, 11 the jambs and 12 the window sill. As usual, the jambs 11 are each provided on its inner face with two parallel grooves 13, 14, formed by an inner 50 molding strip 15, an outer strip 16 and a parting bead 17. Usually these three strips are continuous from the top of the window to the sill 12, but for the purpose of the present invention, the molding strip 15 and 55 parting bead 17 are each formed of two longitudinal sections, divided a few inches

above the meeting rails of the lower sash 18 and the upper sash 19 when the window is closed and connected as shown by a lap joint 20. The upper sections 21 of each molding 60 strip 15 and parting bead 17 are fastened in the usual manner to the window frame by the use of nails. The lower section 22 of each molding strip is held in a straight line with the upper section by means of a swinging 65 latch or tongue 23, pivoted on the upper section 21 and adapted to swing over and retain the lapped end 20 of the lower section 22. Projections of any kind may be provided on the lower section 22 to enter freely 70 into recesses in the jamb 11 and sill 12 to prevent the section slipping. Instead of the swinging latch 23, any other desirable form of fastening may be employed.

The lower section 24 of the parting bead 75 17 is sustained in the same manner as section 22 and maintained in place by a latch 25.

In the sides of each sash are formed 80 grooves 26 that extend longitudinally from top to bottom of the sash. These grooves form seats for metal strips 27 that lie flush with the sides of the sash and permit the sash to slide freely in the window frame 10. Each metal strip 27 is preferably made 85 nearly as long as the groove 26 and has an eye 28 in its upper end to which one end of the sash cord 29 is fastened. The lower end of each strip is bent at a right angle toward the sash to form a foot or hook-like 90 projection 30 that enters a recess 31 in the bottom of the sash. A cross notch 32 is made in the bottom rail of the lower sash 18 at each side which intersects the recess 31 of the same side, each notch being of such 95 size that a swinging or other form of catch 33, seated in a depression 34 in the window sill 12, can enter said notch and pass above the foot 30 of the metal strip 27. Similar cross notches, shown in dotted lines Fig. 2, 100 are made in the under side of the parting rail of the upper sash 19.

With a window equipped with the means described, the sash may be easily removed and replaced without much effort. The 105 lower sash, if raised, is drawn down into closed position and the catches 33 on the window sill engaged with the hook-like projections or feet 30 on the metal strips 27. The catches 33 on the upper sections of the 110 molding strips 15 are then disengaged from the lower sections and the latter removed

from the window. The sash 18 may now be removed without trouble, the catches 33 holding the sash cords and weights from movement and it is only necessary to remove the strips 27 from the grooves 26 in the sides of the sash. The upper sash is removed in the same way after lowering it by disengaging the catches 25 from the lower sections 24 of the parting bead and remove the 10 same, then slip the catches over the inturned ends of the metal strips 27.

It is to be understood that while the construction shown and described is the best form at present known, various changes in 15 the construction and arrangement may be made without departing from the principles of the invention.

I claim:

1. The combination with a window frame 20 and a sash slidable therein, said sash having longitudinal grooves in its side edges; of sash cord attaching strips removably fitted in the grooves flush with the edges of the sash, said strips having angular lower ends 25 extending beneath the bottom rail of the sash, and means on the window frame engageable with said angular lower ends of the strips for holding said strips stationary relative to the sash.

Copies of this patent may be obtained for five cents each, by addressing the "Commissioner of Patents, Washington, D. C."

2. The combination with a window frame 30 and a sash slidable therein, said sash having longitudinal grooves in its side edges; of sash cord attaching strips removably fitted in the grooves flush with the edges of the sash, said strips having angular lower ends 35 extending beneath the bottom rail of the sash, and catches pivoted on the window sill and engageable with said angular lower ends of the strips for holding the same stationary relative to the sash.

3. The combination with a window frame 40 and a sash slidable therein, said sash having longitudinal grooves in its side edges; of sash cord attaching strips removably fitted in the grooves flush with the edges of the 45 sash, said strips having angular lower ends extending beneath the bottom rail of the sash, and catches pivoted on the window sill and engageable with said angular lower ends of the strips for holding the same stationary 50 relative to the sash, that portion of the bottom rail of the sash which is engaged by the angular lower ends of the strips having recesses which are entered by the catches when the same are swung to engage said 55 angular lower ends of the strips.

In testimony whereof I affix my signature.
WILLIAM S. BURKE.
